(57) **CLAIM**

We claim an ornamental design for a finger puppets packaging, as shown and described.

DESCRIPTION

FIG. 1 is a front perspective view of a finger puppets packaging in accordance with the design, wherein finger puppets are secured to finger-like portions.

FIG. 2 is a front perspective view thereof, wherein the finger puppets are removed from the finger-like portions, which are raised to a particular degree;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a rear view thereof, wherein the finger puppets are secured to the finger-like portions;

FIG. 10 is a front view thereof, wherein the finger-like portions are aligned with the packaging; and,

FIG. 11 is a rear view thereof, wherein the finger-like portions are aligned with the packaging.

The portions shown in broken lines form no part of the claimed design.
